UNITED STATES PATENT OFFICE.

EDGAR F. HATHAWAY, OF DORCHESTER, AND CHARLES LEA, OF BOSTON, MASSACHUSETTS, ASSIGNORS TO AMERICAN WASP DRAWING MACHINE COMPANY, OF BOSTON, MASSACHUSETTS, A CORPORATION OF MAINE.

DETACHED HEDDLES AND MEANS AND METHOD FOR ASSEMBLING AND HANDLING THE SAME.

1,149,137.

Specification of Letters Patent.

Patented Aug. 3, 1915.

Application filed October 19, 1908. Serial No. 458,374.

To all whom it may concern:

Be it known that we, EDGAR F. HATHAWAY and CHARLES LEA, both citizens of the United States, and residing, respectively, at Dorchester and Boston, both in the county of Suffolk and State of Massachusetts, have invented an Improvement in Detached Heddles and Means and Methods for Assembling and Handling the Same, of which the following description, in connection with the accompanying drawings, is a specification, like letters on the drawings representing like parts.

Our invention relates to the assemblage of independent detached, thread-engaging, loom elements, such as the detached heddles of a metal-harness, drop wires or drop heddles, or other like devices, the independent members of which are required to be placed in operative association with one or more threads of a loom warp to fulfil some intended purpose in the operation of the loom.

Our invention has for its object the assemblage of a series of heddles, or other like device, in such relation that their separation for any desired purpose, such as the placing of warp threads through or within the control of successive members of the assembled series may be readily effected, while at the same time they may be installed in the loom in their assembled state and perform their usual functions.

These heddles or drop bars as ordinarily constructed are formed of thin sheet metal strips or plates, and are held in an assembled compacted series face to face and with their thin edges exposed. In order to facilitate their separation when assembled in series, it is common to arrange them with an alternating variation in form or position, so that suitable separating mechanism acting with reference to such alternating variation can readily release and separate successive members while holding back the remaining members of the series.

Where an alternately varying formation is procured by removing portions of the heddles or drop wires, either in the form of perforations, indentations in the edges of the heddles or other like formations, such perforations, indentations or other formations, if arranged in alinement, as customarily has been done to provide a continuous passage

or channel for the reception of a separating member, also present such passage or channel for the entrance and accumulation of lint and the like if the heddles or drop bars are installed in the loom in the same relation. This is particularly detrimental in the case of drop heddles or drop wires, which are intended to undergo no movement relatively to each other, except on the breaking of a thread. It has been found that the accumulation of lint in the passage formed by perforations in the successive heddles as described tends to fill up such passage and sustain the heddle independent of the support afforded by its thread, so that if the thread breaks the heddle may fail to drop and perform its intended function.

The object of our invention is to prevent such conditions and to this end we have provided an assemblage of heddles, drop bars or the like presenting perforations, indentations or other formations regularly alternating in form but presenting portions adapted to be brought into line to receive some member of the separating mechanism of a warp drawing or other machine, which perforations, indentations or formations, however, may be put out of alinement when installed in the loom so as to leave no continuous channel or passage for the accumulation of lint.

Our invention will be best understood by reference to the following description when taken in connection with the accompanying illustration of one specific embodiment thereof, while its scope will be more particularly pointed out in the appended claims.

In the drawings: Figure 1 shows in side elevation a common form of drop wire or heddle; Fig. 2 shows the same heddle provided with an alining and a releasing opening; Fig. 3 shows a similar heddle with the releasing opening differently positioned to give an alternating arrangement; Fig. 4 shows in side elevation an assemblage of heddles, alternate members of which are perforated, as are the heddles shown in Figs. 2 and 3; Fig. 5 is a side view of a portion of the series shown in Fig. 4; Fig. 6 is an end elevation showing the heddles with the releasing openings brought into alinement; Fig. 7 shows the same heddles in side elevation; Fig. 8 is a side elevation of the

series illustrating the operation of the releasing mechanism thereon; Fig. 9 shows the same series of heddles co-operatively related to the separating mechanism of a drawing-in machine; Fig. 10 is a detail showing the action of the separating mechanism; and Fig. 11 is a detail showing the releasing key.

For the sake of illustration, we have here-
10 in shown our invention as applied to one particular type of drop wire or heddle, customarily employed for stop motions in connection with the warp of the loom. It is to be understood, however, that this invention
15 has not only general application to drop wires or drop heddles of widely varying and different types or constructions from that shown in the drawings (which is selected solely for the purpose of concrete illustration.) but also has application to the heddles of a metal harness and other similar detached thread-engaging loom elements. Referring to the drawings, however, and the specific embodiment of our invention there
20 selected for illustration, there is shown in Fig. 1 a well-known form of metallic drop heddle, the same consisting of a thin, resilient, sheet-metal plate 1, having a thread-receiving opening 2, herein (though not necessarily) in the form of a circular perforation and having also a portion such as the elongated eye 3 shaped to receive one of the usual contact members in the loom and herein also employed to receive the supporting bar 4 (Fig. 5), upon which the heddles may be held in assembled series prior to placing the threads through the thread apertures thereof and installing the same in the loom.

25 In the disclosed form of heddle we have provided an alternating variation in form between successive heddles, herein by perforating the heddle as at 5 (Fig. 2) and providing a lateral enlargement 6 of such perforation, the enlargement extending in one direction in the case of one heddle and (Fig. 3) in another direction in the case of the next adjacent one. For example, in the case of the heddle shown in Fig. 2, the enlargement projects upwardly, and in the case of the heddle shown in Fig. 3, which is the next successive heddle, the enlargement extends downwardly in the opposite direction. This alternating variation in the formation
30 of the releasing openings in successive heddles makes it possible for them to be engaged as represented in Figs. 8 to 11 by a releasing and separating key 7 connected to the releasing rod 8, the latter extending
35 through the channel or passage formed by the perforations 5 in successive heddles of the assembled mass.

While our invention is not limited to any particular form of separating mechanism, to best understand the utility of the releasing
40

openings, reference may be had to the operation of the separating mechanism shown in Figs. 8 to 11, where the head 7 of the releasing key is provided with an abrupt shoulder 9, which in its operation is caused to overlie and press against the face of the foremost heddle of the compacted series (see Fig. 8) and hold it back together with the rest of the series. As the key is turned, the shoulder 9 is finally turned into registration with the elongation 6 of the releasing perforation for the foremost heddle, and the latter is thereby released and permitted to pass over the head of the releasing key,— the next successive heddle, however, with its oppositely directed elongation, continuing to press against the overlying shoulder of the key and, together with the rest of the series, being held back thereby until the key executes another half turn. It will therefore be seen that the releasing rod, while holding back the body of the heddles, at each half revolution releases the foremost member of that body of series.

The head 7 is provided with a helical formation 10 which is adapted to engage the released heddle and force it along to the extremity of the head where it is discharged. As represented in Fig. 9, the heddle may be discharged to any suitable positioning mechanism, such, for example, as the positioning worm 11 adapted to be rotated by the worm shaft 12, which, together with the key rod 8, extends to suitable actuating mechanism, not herein shown. The positioning worm 11 is so formed as to receive the heddle when discharged from the key, and, after advancing the same, to give it a half turn to place its threading opening 2 in line with the drawing-in needle or other implement, which is qualified to receive a warp thread through the same. Discharge of the threaded heddle from the worm to the series of already threaded heddles follows, and, in this fashion, the releasing key, positioning worm and drawing-in mechanism is caused to advance across the series of heddles.

In order better to effect the release of the successive heddles when the shoulder 9 is brought into registration with the elongated portion of the releasing opening, there may be provided means, such as the carriage 13 which has a curved edge 14 pressing against the end heddle of the series, so as to bend their upper or top ends all slightly outward and thus impart to the foremost bar a tendency to spring over and along the key head 7 when the bar is released.

In order that the releasing openings 5 may be out of alignment when the heddles are installed in the loom, and the formation of the resultant channel or passage thereby prevented, the said openings are not only given an alternative variation in form as between successive members, but are also
125
130

unequally spaced from the threading openings 2. In the described heddle shown in Fig. 2, the opening 5 is located relatively close to the threading opening 2, while in the alternate heddles, as represented in Fig. 3, the releasing opening 5 is further removed from the threading opening. It therefore follows that with the heddles installed in the loom and supported each by a warp thread engaging the supporting walls of its threading opening, the series of threading openings will be substantially in alinement, while the series of releasing perforations will be offset from each other and vertically out of alinement, the relative positions of the successive releasing openings being represented in Fig. 4.

In order that the threading openings may be in substantial alinement when the heddles are suspended on the supporting bar 4, so that, for use in the drawing-in machine, each threading opening will be in approximate alinement with the drawing-in needle, the upper inner edge of the elongated eye 3, which acts to support the heddle by resting on the supporting bar 4 is spaced equi-distant from the threading opening in successive heddles, but differentially from the releasing openings, as will be seen by the contrast between the heddles of Figs. 2 and 3. With the heddles assembled, therefore, as shown in Figs. 4 and 5, and suspended in a compacted mass upon the supporting bar 4, the releasing openings are offset from each other and out of alinement.

In order to aline the releasing openings of the assembled heddles for the reception of the key rod 8, we have provided suitable alining means. While this alinement may be provided for in various ways, herein we have provided as an alining formation for each heddle, the circular enlargement 15 near the bottom of the elongated eye 3. These comprise in effect openings of substantially the same diameter spaced equi-distant from the releasing openings 5 in the case of each heddle, but differentially spaced in successive heddles relatively to the threading openings 2. While the alining openings in successive heddles are out of line as the heddles hang upon the supporting bar 4, they are so arranged that successive alining openings overlap leaving a continuous channel 16 (Fig. 4) through the assembled heddles of slightly greater width than the eye 3.

With the drop wires assembled on the supporting bar, an alining member 17, comprising a rod of substantially the diameter of the alining openings 14 and having a tapered point 18, may be inserted in the widened channel 16 and forced through the entire series of heddles, as indicated in Fig. 7, this operation causing successive heddles

to be raised up from the supporting bar 4 and bringing the releasing perforations 5 into alinement. With the heddles in this condition the key rod 8 can then be installed in the channel formed by the perforations 5 and its end connected with the driving mechanism in the machine preparatory to the separating and selecting operation, the alining member 17 thereupon being withdrawn (see Figs. 8 and 9) leaving the series of heddles in condition for the separating and drawing-in operation. During the separating action a portion only of the unthreaded heddles rest upon the supporting bar, each alternate one being supported at the key rod 8. As the alternate elevated heddles are released and discharged from the key rod, they are dropped to a lower level and, in their subsequent movement, are suspended upon the supporting bar 4.

While we have shown and described one specific embodiment of our invention and have shown for sake of illustration one specific application thereof, it is to be understood that our invention is not limited to the particular details herein shown or to the application thereof herein made, but that it is susceptible of extensive modification and deviation from the described construction, and may be usefully applied to purposes other than those herein described.

Having thus described our invention, what we claim is:

1. A series of independent thread-engaging loom elements, such as drop wires, detached heddles or the like, each having a threading opening and a releasing opening, successive releasing openings being differentially arranged to present an alternate variation in form between successive members of the series, each member being provided near its top with an elongated supporting eye to receive a supporting bar, said threading and releasing openings being so positioned relatively to the supporting eye that when the members are hung upon the supporting bar the threading openings of successive members are in alinement and the releasing openings out of alinement, the supporting eye of each member having also an alining opening comprising a circular enlargement near its lower end and adapted to receive a pointed rod, the said enlargements being equi-distant from the releasing openings but offset each from the other in successive members while overlapping each its adjacent one, whereby on the insertion of an alining rod alternate members may be raised from the supporting bar and the releasing openings alined permitting the insertion therethrough of a suitable releasing member.

2. A series of independent thread-engaging loom elements, such as detached drop

- wires, heddles or the like, each having a threading opening and a releasing opening, successive releasing openings being differentially arranged to present an alternate variation in form between successive members of the series, each member being provided with supporting edges to engage a supporting bar, said threading and releasing openings being so positioned to the supporting edges that when the members are suspended upon the bar the threading openings of successive members are in alinement and the releasing openings out of alinement, a circular opening in each member adapted to receive a point of an alining rod, the said openings being equi-distant from the releasing openings but offset each from the other in successive members, while overlapping each its adjacent one, whereby on the insertion of the rod alternate members may be raised from the supporting bar and the releasing openings alined, permitting insertion therethrough of a suitable releasing member.
3. An assemblage of independent thread-engaging loom elements, such as drop wires, detached heddles or the like, each having a threading opening and a releasing opening, successive releasing openings being differentially arranged to present an alternate variation in form between successive members, means to support the assembled members with the successive releasing openings out of alinement, said members being also provided with alining openings of similar form and adapted to receive an alining member, said openings in successive members being offset but overlapping and located equi-distant from the releasing openings.
4. An assemblage of independent thread-engaging loom elements, such as drop wires, detached heddles or the like, having each a threading opening and a releasing opening, successive releasing openings being differentially arranged to present an alternate variation in form between successive members, means to support the assembled members with releasing openings out of alinement, and means to support said members with the said openings in alinement.
5. An assemblage of independent thread-engaging loom elements, such as drop wires, detached heddles or the like, each having a threading opening and a releasing opening, means to support the members of the series with the releasing openings out of alinement, and means to support the same with said openings in alinement.
6. An assemblage of independent thread-engaging loom elements, such as drop bars, detached heddles or the like, having releasing openings out of alinement when supported in the loom, and means for alining the same prior to installation in the loom.
7. An assemblage of independent thread-engaging loom elements, such as drop bars, detached heddles or the like, presenting alternate varying formations normally out of line, and means for bringing such alternate formations into line.
8. An assemblage of independent thread-engaging loom elements, such as drop bars, detached heddles or the like, each having a threading opening, means for supporting the same with the threading openings in line, and means to support the same with the threading openings out of line.
9. An assemblage of independent thread-engaging loom elements, such as drop bars, detached heddles or the like, each having a threading opening and alining means differentially spaced for successive members from the said threading openings.
10. An assemblage of independent thread-engaging loom elements, such as drop bars, detached heddles or the like, each having supporting edges for supporting the series in a warp drawing machine, differentially spaced, cut away portions for successive heddles, and alining means adapted to be engaged by a suitable alining member to bring the said cut away portions into alinement.
11. An assemblage of independent thread-engaging loom elements, such as drop bars, detached heddles or the like, each having a releasing opening, successive openings being differentially arranged to present an alternate variation in form between successive members, the said releasing openings being also differentially located on successive members.
12. An assemblage of independent thread-engaging loom elements, such as drop bars, detached heddles or the like, presenting alternately varied cut away portions for engagement with suitable releasing mechanism, and alining means for alining the said cut away portions.
13. An independent detached heddle having a threading opening, a releasing opening and an alining opening.
14. An independent detached heddle having an elongated eye, a circular enlargement therein, a threading opening and a releasing opening provided with a lateral enlargement.
15. An assemblage of drop wires having each a threading opening with edges adapted to support the drop wire on its thread in the loom, said drop wire presenting openings differentially spaced for successive members from the said supporting edges.
16. An assemblage of drop wires having each a threading opening with edges adapted to support the drop wire on its thread in the loom, said drop wire presenting alternately varied cut away portions differentially spaced for successive members from the said supporting edges.

17. The combination with a series of independent thread-engaging loom elements, such as drop wires, heddles or the like, presenting alternately varied formations normally held out of alinement while in the loom, of means for coöperating with the said alternate formations and releasing successive members of the series for engagement with suitable thread-drawing mechanism prior to installation in the loom. 40
18. The method of separating a compacted series of thread engaging loom elements having threading openings such as drop wires preparatory to the drawing-in operation which consists in holding said series in compacted relation, shifting each alternate drop wire to place the threading openings out of alinement, releasing the foremost drop wires of the series in succession, then placing a warp thread through the threading opening of each successive drop wire and shifting each successive drop wire to again bring the threading openings into alinement. 50
19. The method of handling thread-engaging loom elements such as drop wires having threading openings prior to insertion in the loom, which consists in holding the same in series with the threading openings out of alinement, releasing successive members from the series and then replacing the said drop wires in the series with the threading openings in alinement. 60
20. The method of handling thread-engaging loom elements having threading openings such as drop wires, which consists in compacting them with the threading openings out of alinement, separating each one singly out of the compacted mass and placing its threading opening in alinement with the threading openings of the preceding elements, threading each element and placing the elements in the loom. 65
21. The method of handling thread engaging loom elements having threading openings such as drop wires prior to insertion in the loom which consists in holding the same in series releasing successive members from the series with the threading openings out of alinement, drawing a warp thread through the threading opening of each successive drop wire, and then replacing drop wires in the series with the threading openings in alinement. 70
22. A series of drop bars 1, having threading openings 2 and releasing openings 5—5, alternate releasing openings being differentially located relatively to the threading openings. 75
23. A series of drop bars having each a threading opening and a releasing formation, the said series comprising two sets, said bars having each supporting edges which are differently spaced from the threading openings in the two sets, and having also other supporting edges which are differently spaced from the releasing formations in the two sets. 80
- In testimony whereof, we have signed our names to this specification, in the presence of two subscribing witnesses.

It is hereby certified that the assignee in Letters Patent No. 1,149,137, granted August 3, 1915, upon the application of Edgar F. Hathaway, of Dorchester, and Charles Lea, of Boston, Massachusetts, for an improvement in "Detached Heddles and Means and Methods for Assembling and Handling the Same," was erroneously described and specified as "American Wasp Drawing Machine Company," whereas it should have been described and specified as *American Warp Drawing Machine Company*, as shown by the records of assignments in this office; and that the said Letters Patent should be read with this correction therein that the same may conform to the record of the case in the Patent Office.

Signed and sealed this 31st day of August, A. D., 1915.

[SEAL.]

J. T. NEWTON,

Acting Commissioner of Patents.
